UNITED STATES PATENT OFFICE

NOTEN CHANEY, OF DANNEMORA, NEW YORK

ENDLESS CLOTHESLINE

Application filed February 4, 1929. Serial No. 337,465.

This invention relates to clothes dryers, and has for one of its objects to provide a novel, simple and highly efficient device of this character which shall embody an endless clothes line, means for supporting the clothes line from and between opposing walls of buildings or from a wall of a building and a post in the yard of the building or other suitable supports, and means associated with said first

10 means for operating the clothes line so as to permit the clothes to be applied thereto or removed therefrom adjacent one end thereof.

The invention has for a further object to provide a device of the character stated

15 wherein the clothes line supporting means shall embody brackets of strong and durable construction and adapted to be secured firmly to the supports, and wherein said means shall embody horizontally disposed pulleys journaled on the brackets and having the clothes line engaged therewith.

The invention has for a further object to provide a device of the character stated which shall embody means carried by the brackets

25 and adapted to prevent the weight of the clothes from displacing the clothes line from its supporting pulleys.

The invention has for a still further object to provide a device of the character stated

30 which shall embody means carried by the brackets and adapted to guide the clothes supporting clips over the means for preventing the displacement of the clothes line and adapted to guide the clips around the clothes line supporting pulleys.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view in side elevation of the clothes dryer;

Figure 2 is a top plan view of the clothes dryer;

Figure 3 is a sectional view taken on the vertical plane indicated by the line 3—3 of Figure 1;

Figure 4 is a sectional view taken on the

vertical plane indicated by the line 4—4 of Figure 1;

Figure 5 is a sectional view taken on the vertical plane indicated by the line 5—5 of Figure 1, and

Figure 6 is a sectional view taken on the vertical plane indicated by the line 6—6 of Figure 1.

The clothes dryer comprises brackets 1 and 2 which are adapted to be secured to the supports and are substantially similar and made from angle iron. The brackets 1 and 2 each comprises a vertical member or arm 3, a horizontal member or arm 4, and a brace 5. The brackets 1 and 2 are secured to the supports

60 by bolts 6 engaged with the supports and passing through the arms 3. The arms 4 extend inwardly from the lower ends of the arms 3, and the braces 5 extend from points adjacent the upper ends of the arms 3 to

65 points adjacent the inner ends of the arms 4.

The brackets 1 and 2 are each provided with an axle 7 which extends downwardly from its arm 4 and is fixedly secured thereto at a point between the lower ends of its arm 3 and brace 5. A horizontal pulley 8 is journaled on the axle 7 of the bracket 1, and a horizontal pulley 9 is journaled on the axle 7 of the bracket 2. The pulleys 8 and 9 are supported upon the axles 7 by nuts 10. The pulleys 8 and 9 are similar and each is provided with a peripheral groove 11 and a peripheral flange 12 located below the groove and constituting an extension of one of the walls thereof. An endless clothes line 13 is trained about the pulleys 8 and 9, and to permit it to be moved, so as to permit the clothes to be applied thereto and removed therefrom, the pulley 8 is provided with a handle 14 which extends downwardly therefrom at a point near its periphery.

The clothes line 13 is maintained on the pulleys 8 and 9, against the tendency of the weight of the clothes to displace it, by the pulley flanges 12 and by the pulleys 15. A pair of the auxiliary pulleys 15 is associated with each of the main pulleys 8 and 9. The pulleys 15 are arranged inwardly of the pulleys 8 and 9 and in alinement with the outer peripheral portions of said latter pulleys

100

as to permit the opposite sides or runs of the clothes line 13 to rest thereon, the auxiliary pulleys being provided with peripheral grooves for the reception of the clothes line. 5 Each of the brackets 1 and 2 is provided with a cross bar 16 of inverted U-form and secured, as at 17, to the arm 4 of the bracket. The cross bars 16 are secured to the arms 4 inwardly beyond the pulleys 8 and 9, and they 10 extend transversely of said arms and have their downwardly extending members provided with axles 18. The pulleys 15 are journaled upon the axles 18, and are maintained thereon by nuts 19. 15 The cross arm 16 of the bracket 1 is secured to the inner end of the arm 4 of the bracket. The cross arm 16 of the bracket 2 is secured to the arm 4 of the bracket outwardly beyond the inner end thereof at a 20 point between said end and the pulley 5. This arm 4 is provided with a downturned inner end 20, and guards 21 are secured, as at 22 to said portion of the arm. The guides 21 curve laterally, upwardly and outwardly 25 from the arm portion 20 to points above the axles 18 of the bracket 2, and the guides curve downwardly from said points to points beneath the pulley 9. The guards 21 are also supported from this axle 8, the guards being 30 provided for this purpose with arms 22 which are arranged between their ends and extend downwardly therefrom to the axle. The arms 22 are provided with openings for the reception of the axle, and are retained thereon by 35 the nuts 9.

The clothes are secured to the endless line 13 preferably by members 23. Only one of the clothes attaching members 23 is shown. Each clothes attaching member 23 consists 40 of angularly related spring clips 24 and 25, the former being adapted to be engaged with the endless line 13 and the latter with the article to be dried, the article being shown in dotted lines and designated 26.

45 The clothes dryer is especially adapted for use by occupants of tenements, and it will preferably be secured to suitable supports with the bracket 1 located near a porch, window or fire escape, if desired, the bracket 1 50 may be secured directly to the porch, window frame or fire escape, and the bracket 2 secured to a wall or other suitable support opposite the porch, window or fire escape. If it is found desirable to do so the brackets 55 1 and 2 may be secured to windows, porches or fire escapes arranged opposite each other, and when this is done the occupants of two dwellings may use the clothes line, and each of the brackets will be provided with a pulley turning handle 14 and with guards 21.

The person using the clothes dryer preferably stands in close proximity to the bracket 1 so as to permit the convenient adjustment 60 of the endless line 13 through the medium 65 of the handle 4. The line is adjusted to carry

the clothes away from the operator as they are attached to the line and adjusted to carry the clothes in the direction of the operator while they are being removed from the clothes line. The guards 21 function to carry the 70 article attaching members 23 over the auxiliary pulleys 15 and around the main pulleys 8 and 9 without any liability of the members becoming interlocked with such parts.

It should be apparent from the foregoing 75 description, taken in connection with the accompanying drawing, that the clothes dryer is simple, strong and practically indestructible, that its brackets may be firmly secured to the supports, and that the brackets are of such construction as to prevent any downward bending of the horizontal arms under the weight borne thereby. It will also be apparent that the clothes dryer may be manufactured and sold at a comparatively low cost. 80 85

While I have described the principle of the invention together with the structure which I now consider to be the best embodiment thereof, I wish it understood that the structure shown is merely illustrative, and that such changes may be made therein when desired as are within the scope of the invention and claimed.

What I claim is:

A device of the character set forth, comprising brackets having horizontal arms, one of said arms being provided with a downturned inner end, horizontal pulleys journaled on said arms between their ends, an endless line carried by said pulleys, cross bars carried by said arms, vertical pulleys journaled on the cross bars and supported thereby, and guides associated with the arm having the downturned inner end and extending from said end to points above said 100 second pulleys and from said points to points below said first pulleys.

In testimony whereof I affix my signature.
NOTEN CHANEY.
